UNITED STATES PATENT OFFICE.

JOSEPH HIRSCH, OF KANSAS CITY, MISSOURI.

DESIGN FOR A HORSESHOE-CALK.

SPECIFICATION forming part of Design No. 35,207, dated October 22, 1901.

Application filed April 22, 1901. Serial No. 57,026. Term of patent 14 years.

To all whom it may concern:

Be it known that I, JOSEPH HIRSCH, a citizen of the United States, residing at Kansas City, in the county of Jackson and State of Missouri, have invented and produced a certain new and original Design for Horseshoe-Calks; and I do declare the following to be a full, clear, and exact description of the invention, such as will enable others skilled in the art to which it appertains to make and use the same.

The invention relates to a new and original design for horseshoe-calks; and it consists of the design of the configuration shown in the accompanying drawings, in which—

Figure 1 is a perspective view. Fig. 2 is a top plan view, and Fig. 3 is a vertical sectional view through the shank of the calk.

The leading feature of the design comprises a calk 1, the rear face of which is arranged in a vertical plane and the front face of which

is beveled from its lower end to a point midway the ends of the calk, the shank 3 projecting forwardly from the vertical forward straight face of the calk and having its upper surface arranged in the same horizontal plane as the surface of the upper end of the calk and polygonal in cross-section, the sides from the upper surface converging downwardly, said shank being of less width than the calk, and the groove 2 in the rear face of the calk.

What I claim is—

The design for a horseshoe-calk, as herein shown and described.

In testimony whereof I have hereunto set my hand in presence of two subscribing witnesses.

JOSEPH HIRSCH.
